US00D636094S

(12) **United States Design Patent**
Mugge

(10) **Patent No.:** **US D636,094 S**
(45) **Date of Patent:** **** Apr. 12, 2011**

(54) **MOLDED SURFACE OF A CONCRETE PRODUCT**

(75) Inventor: **Jimmie L. Mugge**, Inver Grove Heights, MN (US)

(73) Assignee: **Anchor Wall Systems, Inc.**, Minnetonka, MN (US)

(**) Term: **14 Years**

(21) Appl. No.: **29/370,893**

(22) Filed: **Sep. 17, 2010**

Related U.S. Application Data

(62) Division of application No. 29/348,537, filed on Jan. 15, 2010, now Pat. No. Des. 625,840, which is a division of application No. 29/315,578, filed on Jul. 6, 2009, now Pat. No. Des. 611,164, which is a division of application No. 29/313,088, filed on Dec. 4, 2008, now Pat. No. Des. 598,136, which is a division of application No. 29/270,117, filed on Dec. 14, 2006, now Pat. No. Des. 584,423.

(57) **CLAIM**

The ornamental design for a molded surface of a concrete product, as shown and described.

DESCRIPTION

FIG. 1 is a perspective view of a molded surface of a concrete product;

FIG. 2 is a front elevational view thereof;

FIG. 3 is a top view thereof;

FIG. 4 is a bottom view thereof;

FIG. 5 is a right side view thereof; and,

FIG. 6 is a left side view thereof.

The broken lines in the drawing views are included for the purpose of illustrating portions of the molded surface of a concrete product that form no part of the claimed design.

1 Claim, 6 Drawing Sheets
